L. W. SIBLEY, OF AMES, IOWA.

Letters Patent No. 91,677, dated June 22, 1869.

IMPROVEMENT IN GATES.

The Schedule referred to in these Letters Patent and making part of the same

To all whom it may concern:

Be it known that I, L. W. SIBLEY, of Ames, in the county of Story, and State of Iowa, have invented a new and useful Improvement in Gates; and I do hereby declare that the following is a full, clear, and exact description thereof, which will enable others skilled in the art to make and use the same, reference being had to the accompanying drawing, forming part of this specification, in which—

Figure 1 is a detail sectional view of my improved gate, taken through the line $x-x$, fig. 2.

Figure 2 is a top or plan view of the same.

Figure 3 is a detail view, showing the hinge.

Similar letters of reference indicate corresponding parts.

My invention has for its object to furnish an improved gate, which shall be so constructed and arranged that it may be opened by the advancing, and closed by the departing wagon; and

It consists in the construction and combination of the various parts, by means of which the gate is operated, as hereinafter more fully described.

A represents the gate; B, the rear gate-post; C, the front gate-post; about the construction of which parts there is nothing new.

The gate A is hinged to the post B by means of eye-bolts D, attached to the rear vertical bar of the gate, and long staples E, attached to the post B, as shown in fig. 3.

F is a circular rail or track, made upon the arc of a circle, having its centre in the axis of the gate.

The track F is formed solidly upon, or securely and rigidly attached to the arms of a U-shaped bar, G, the centre of which is swivelled to the forward side of the lower part of the post D, by means of a headed projection, pin, or bolt formed upon or attached to the outer side of the centre of the said U-shaped bar G, which enters a socket formed in the said post B for its reception.

For convenience in inserting and detaching the track F G, a slot may be formed, leading upward from said socket, and widened at its upper end, so as to admit the head of said bolt, pin, or projection.

The ends of the arms of the U-shaped bolt G rest upon pivots, the points of which enter sockets in said arms, and which are placed equally distant from the centre of the circular track F.

H is a grooved wheel or pulley, pivoted to the lower part of the gate A, in such a position as to rest upon the track F, and roll along said track as the gate is swung open and shut.

To the ends of the curved track F are attached the

ends of two ropes, or chains I, which pass beneath and around grooved pulleys J, pivoted to suitable supports in a channel beneath the gate. The ropes or chains I cross each other beneath the gate, and extend out for a sufficient distance upon the opposite sides of said gate.

The outer ends of the chains I are branched, and the ends of the branches are attached, the one to the upper side, and the other to the lower side of the eccentric wheels, or pulleys K, which may be grooved partly or wholly around their faces, and which are rigidly attached to the shafts L, which extend out horizontally with the surface of the ground, and upon the ends of which are formed cranks M.

The eccentric pulleys K and cranks M should be so arranged that the longer radius of the said pulleys K and the crank-arms M should be directly opposite to each other, as shown in fig. 1, so that the weight of the pulleys K, when left free to act, may always raise the cranks M into a vertical position. By this construction, as the wagon or other vehicle approaches the gate, the wheel strikes the upwardly-projecting crank M, and forces it down towards the gate, which depresses the further end, and elevates the nearer end of the track F.

The first effect of this movement is to raise the gate and unlatch it. The weight of the gate then causes the wheel H to roll down the inclined track F, swinging the gate open in the direction from the advancing vehicle, the weight of the gate holding the track inclined after the wheel has left the crank M.

As the vehicle passes through the gate, its wheel strikes the other crank M, and forces it down in a direction from the said gate.

This movement of the crank M brings the track F back into its former position, so that the gate, by its own weight, will swing shut, latching itself.

Having thus described my invention, What I claim as new, and desire to secure by Letters Patent, is—

1. The curved tilting track F G, constructed and operating substantially as herein shown and described, and for the purpose set forth.

2. The combination of the grooved wheel H, tilting track F G, ropes or chains I, pulleys or wheels J, eccentric wheels K, and cranks M, with each other and with the gate A, substantially as herein shown and described, and for the purposes set forth.

L. W. SIBLEY.
